UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

FRICITION DRAFT-RIGGING FOR RAILWAY-CARS.

No. 862,991.

Specification of Letters Patent.

Patented Aug. 13, 1907.

Application filed June 12, 1907. Serial No. 378,486.

To all whom it may concern:

Be it known that I, JOHN F. O'CONNOR, a citizen of the United States, residing in Chicago, in the county of Cook and State of Illinois, have invented a new and useful Improvement in Friction Draft-Rigging for Railway-Cars, of which the following is a specification.

My invention relates to friction draft rigging for railway cars.

The object of my invention is to provide a friction draft rigging having a direct acting spring longitudinally arranged in the line of draft so as to have a direct spring cushioning effect, and having also a plurality of coöperating friction elements or devices each and all coöperating to furnish a frictional resistance to aid in cushioning the draw-bar, and which will be of a strong, simple, efficient and durable construction, and not liable to be broken or injured.

My invention consists in the means I employ to practically accomplish this object or result as herein shown and described, the same being more particularly specified in the claims.

In the accompanying drawing forming a part of this specification, Figure 1 is a side elevation partly in longitudinal vertical section of a friction spring draft rigging embodying my invention. Fig. 2 is a plan view partly in horizontal section. Fig. 3 is a vertical cross section on line 3—3 of Fig. 2. Fig. 4 is a detail side elevation of one of the hinged segmental cylindrical friction shoes. Fig. 5 is a detail elevation of one of the friction shoe followers showing its friction face. Fig. 6 is a similar view showing its opposite face. Fig. 7 is a detail view of one of the outer semi-cylindrical friction shoes; and Fig. 8 is a detail plan view partly in horizontal section.

35 In the accompanying drawing, A represents the center sills, draft timbers or other longitudinal frame members of the car to which the draft rigging is applied. A¹ is the front or cross sill. B is the draw-bar, B¹ the draw-bar yoke secured to the draw-bar by rivets b, C C the abutment shoulders or stops secured to the draft timbers or other longitudinal frame members of the car, and against which the main followers D D of the draft rigging abut. The main followers D D are each furnished with an inner semi-cylindrical friction face d.

45 E e are longitudinally arranged direct acting springs interposed between the main followers D D in the line of draft and inclosed within the hollow cylindrical quadrant hinged friction shoes F F¹ and F F¹. Each of the friction shoes F F¹ has an exterior friction face f in sliding frictional engagement with the cylindrical friction face d of the main followers D D. And each of these segmental cylindrical hinged friction shoes F F¹ is also furnished with an internal cylindrical friction face f¹, which is in sliding frictional engagement with the spring

engaging segmental cylindric friction shoe followers G, 55 each of which is furnished with an external cylindric friction-face g. Each of the cylindrically faced spring engaging friction follower shoes G is also preferably furnished with an integral hub or stud g¹, which fits within the inner spring e as a guide to hold the spring 60 in place. The quadrant or segmental cylindric hinged friction shoes F F¹ are preferably hinged together by pins f², which pass through interfitting hinge lugs f³ on these friction shoes F. H is a removable tie or guide plate removably connected to the center sills or other 65 draft timbers A by bolts h and by which the main followers and draft rigging as a whole is supported and guided.

In operation, by movement of the draw-bar in either direction, the longitudinally arranged spring is directly 70 compressed between the front and rear main followers D D which also act as friction shoes against the exterior friction faces of the four segmental or quadrant shaped cylindric hinged friction shoes F F¹, F F¹, thus contracting the same and causing the same to also exert a frictional resistance at their internal friction faces against the spring engaging friction shoe followers G G, so that the draw-bar is effectually cushioned not only by the direct acting spring but also by the frictional resistance 75 of all the several movable friction devices which are 80 interposed between the spring and the draw-bar or its yoke. By this means, I produce a very simple, strong and compact friction spring draft rigging, and one which operates efficiently and releases with certainty and reliability.

I claim:

1. In a friction spring draft rigging, the combination with the stops, draw-bar, direct acting spring and a pair of main followers having inner curved friction faces, hinged segmental friction shoes having external and internal curved friction faces and a pair of spring engaging friction shoe followers having external friction faces engaging the internal friction faces of the hinged friction shoes, substantially as specified.

2. In a friction spring draft rigging, the combination 95 with the stops, draw-bar, direct acting spring and a pair of main followers having inner curved friction faces, hinged segmental friction shoes having external and internal curved friction faces and a pair of spring engaging friction shoe followers having external friction faces engaging the internal friction faces of the hinged friction shoes, said hinged friction shoes being hinged together in pairs, substantially as specified.

3. In a friction spring draft rigging, the combination 105 with the stops, draw-bar, direct acting spring and a pair of main followers having inner curved friction faces, hinged segmental friction shoes having external and internal curved friction faces and a pair of spring engaging friction shoe followers having external friction faces engaging the internal friction faces of the hinged friction shoes, said spring engaging friction shoe followers having central hubs to guide or support the springs, substantially as specified.

4. In a friction spring draft rigging, the combination with the stops, draw-bar, direct acting spring, and a pair of main followers having inner curved friction faces, hinged segmental friction shoes having external and internal curved friction faces and a pair of spring engaging friction shoe followers having external friction faces engaging the internal friction faces of the hinged friction shoes, said hollow hinged friction shoes being hinged together in pairs on upright hinges, one on each side of the draw-bar, substantially as specified. 35
5. In a friction spring draft rigging, the combination with the draw-bar, a longitudinally arranged direct acting spring, a pair of main followers having inner semi-cylindrical friction faces, hollow segmental friction shoes surrounding said spring and having external and internal curved friction faces and spring engaging followers having external friction faces engaging the internal friction faces of said hollow friction shoes, substantially as specified. 40
- 10 6. In a friction spring draft rigging, the combination with the draw-bar, a longitudinally arranged direct acting spring, a pair of main followers having inner semi-cylindrical friction faces, hollow segmental friction shoes surrounding said spring and having external and internal curved friction faces and spring engaging followers having external friction faces engaging the internal friction faces of said hollow friction shoes, substantially as specified. 45
- 15 7. In a friction spring draft rigging, the combination with the draw-bar, a longitudinally arranged direct acting spring, a pair of main followers having inner semi-cylindrical friction faces, hollow segmental friction shoes surrounding said spring and having external and internal curved friction faces and spring engaging followers having external friction faces engaging the internal friction faces of said hollow friction shoes, substantially as specified. 50
- 20 8. In a friction spring draft rigging, the combination with the draw-bar, of a longitudinally arranged direct acting spring, a pair of main followers having inner curved friction faces and hollow segmental friction shoes surrounding said spring and interposed between the same and said main followers, and having external curved friction faces in frictional engagement with the curved friction faces of said main followers, substantially as specified. 55
- 25 9. In a friction spring draft rigging, the combination with the draw-bar, of a longitudinally arranged direct acting spring, a pair of main followers having inner curved friction faces and hollow segmental friction shoes surrounding said spring and interposed between the same and said main followers, and having external curved friction faces in frictional engagement with the curved friction faces of said main followers, said segmental friction shoes being hinged together in pairs, substantially as specified. 60
- 30 7. In a friction spring draft rigging, the combination with the draw-bar, a longitudinally arranged direct acting

spring, a pair of main followers having inner semi-cylindrical friction faces, hollow segmental friction shoes surrounding said spring and having external and internal curved friction faces and spring engaging followers having external friction faces engaging the internal friction faces of said hollow friction shoes, said hollow segmental friction shoes having integral interfitting hinge lugs connecting them together in pairs, substantially as specified. 65

8. In a friction spring draft rigging, the combination with the draw-bar, of a longitudinally arranged direct acting spring, a pair of main followers having inner curved friction faces and hollow segmental friction shoes surrounding said spring and interposed between the same and said main followers, and having external curved friction faces in frictional engagement with the curved friction faces of said main followers, substantially as specified. 70

9. In a friction spring draft rigging, the combination with the draw-bar, of a longitudinally arranged direct acting spring, a pair of main followers having inner curved friction faces and hollow segmental friction shoes surrounding said spring and interposed between the same and said main followers, and having external curved friction faces in frictional engagement with the curved friction faces of said main followers, said segmental friction shoes being hinged together in pairs, substantially as specified. 75
